UNITED STATES PATENT OFFICE.

CHARLES J. MARTH, OF ST. LOUIS, MISSOURI, ASSIGNOR TO WAYNE MANUFACTURING COMPANY, OF ST. LOUIS, MISSOURI, A CORPORATION OF MISSOURI.

GEARING.

1,080,151.

Specification of Letters Patent.

Patented Dec. 2, 1913.

Application filed July 24, 1912. Serial No. 711,245.

To all whom it may concern:

Be it known that I, CHARLES J. MARTH, a citizen of the United States, residing in the city of St. Louis and State of Missouri, have 5 invented a new and useful Gearing, of which the following is a specification.

This invention relates to gearings of the motor driven type, and an object of the invention is to provide a washing machine 10 and the driving mechanism therefor with an equipment for automatically disabling the driving mechanism as an incident to a change in the position or adjustment of the tub.

15 Another object is to provide a bench or support and a tub pivotally supported upon said bench or support and equipped with an agitator, in combination with power mechanism for operating the agitator, a device for 20 holding the tub stationary in one position, and means for disabling the power mechanism when the tub is moved to another position on said bench or support.

In the drawings in which I have illustrated 25 one embodiment of my invention, Figure 1 is a plan view of the bench, and shows the tub pivotally mounted on the bench and a part of the power mechanism for operating the agitator. Fig. 2 is a side 30 elevation of the apparatus, and illustrates the lever which is operated incidentally to the tilting or inclination of the tub to disable the power mechanism to the extent of breaking the operative connection between the 35 power mechanism and the agitator. Fig. 3 is another side or front view of the apparatus. Fig. 4 is a detail view, enlarged with respect to the preceding views, showing the lever and clutch device which are operated 40 incidentally to tilting or inclination of the tub to break the operative connection between the power mechanism and the agitator. Fig. 5 is a side elevation of the mechanism shown in Fig. 4. Fig. 6 is a detail 45 view of the supporting latch which holds the tub in position for use.

The bench or support consists of an open 50 frame 1 supported by legs or posts 2 suitably strengthened and reinforced by cross pieces and braces. The tub 3 has trunnions 4 attached to opposite sides thereof and journaled in bearings 5 attached to the side members of the bench or frame 1. The said trunnions are not disposed diametrically opposite to each other, but are arranged so that

the tub will readily tilt thereon because the greater weight of the tub is at one side of said trunnions. A bracket bearing 6 is attached to the side of the tub substantially midway of the greater space between the 60 trunnions and supports a revoluble member 7. The member 7 is substantially vertical and has an arm 8 rigid with its lower end. When the member 7 is adjusted to position the arm 8 at right angles to the surface of 65 the tub, said arm 8 extends over one of the side members of the bench 1. A latch member 9, consisting of a plate having upwardly extending flanges, is secured to the upper side of the bench 1 in position to be engaged 70 by the arm 8. The arm 8 thus supports the tub substantially level as shown in Figs. 2 and 3, and the flanges on the ends of the latch member 9 prevent accidental turning of the arm 8, and affords assurance against 75 accidental tilting of the tub. The member 7 is provided with a flange or collar 10 which prevents longitudinal movement of said member 7 through the bearing 6.

A hand lever 11 is rigid with the member 7, at right angles to the arm 8, and some distance, say about four to six inches, above the arm 8. After slightly raising the tub to disengage the arm 8 from the latch member 9, the member 7 may be turned to the position 80 shown by dotted lines in Fig. 6 in which the lever 11 extends over the side of the bench 1 and the arm 8 is free to pass inside of the side member of the bench. This permits the tub to tilt or incline as shown in dotted lines 85 in Fig. 2, the lever 11 constituting a stop to engage with the side member of the bench and hold the tub from further tilting. Below the member 7, the tub is provided with a drain passage 12 through which the fluid 90 contents of the tub may be drawn off. The passage 11 is normally closed by means of a stopper or plug or other suitable device. A handle 13 is attached to the side of the tub above the bearing 6 for manual engagement 95 in raising and lowering the tub.

The agitator shaft 14 extends through the bottom of the tub and is entrained with a shaft 15 which is journaled in bearings carried by a bracket 16 attached to and moving 105 with the bottom of the tub. A sprocket 17 is loosely mounted on the shaft 15 and is connected with a sprocket wheel 18 on a drive shaft 19 by means of a chain 20. The shaft 19 is arranged to be constantly rotated and to 110

transmit motion to the shaft 15 through the medium of the chain 20 and the wheel 17. A sleeve 21 is feathered on the shaft 15 and is arranged to interlock with the hub of the wheel 17 as shown at 22 in Fig. 4. One of the braces or cross pieces of the bench carries a support 23 to which a lever 24 is pivoted. Said lever 24 is slotted and engages within an annular groove in the sleeve 21, so that said sleeve 21 may be operated by manipulation of said lever. The sleeve 21 constitutes a clutch for locking the wheel 17 upon the shaft 15, and the lever 24 is operable to open and close the clutch. An arm 26 extends outwardly from the side of the bench and the lever 24 is provided with a lug 27 arranged to engage in notches 28 in the arm 26 to hold the clutch in open or closed adjustment, as desired. This enables the clutch to be held open or closed, as desired, when the tub is in its level adjustment.

When the tub is being tilted or inclined to the position shown by dotted lines in Fig. 2, the lever 24 is automatically operated to open the clutch incidentally to the movement of the tub. As the tub moves downwardly when being tilted the shaft 15 swings backwardly as shown by dotted lines in Figs. 2 and 5, thereby moving the lever 24 toward the position of said lever shown by dotted lines in Figs. 2 and 5. In this movement the lever 24 engages a cam plate 29 attached to the side of the bench, and is thereby forced outwardly to disengage the clutch 21 from the hub of the wheel 17, leaving said wheel loose and free to turn upon and independently of the shaft 15. Thus the operative connection between the driving mechanism and the agitator is automatically broken or separated as an incident to the tilting or inclination of the tub.

Having thus fully described my invention what I claim and desire to secure by Letters Patent is—

1. The combination with a support, a shaft carried by said support, a drive shaft, a connection for driving said first-named shaft from said drive shaft, and means for supporting said support in different adjustments, of automatic means for rendering said connection inoperative incidentally to the movement of said support from one to the other of said adjustments, substantially as specified.

2. The combination with a bench, a support pivoted on said bench, means for holding said support in different adjustments, a shaft carried by said support, a drive shaft, connections from said drive shaft for rotating said first-named shaft when said support is in one of said adjustments, and a lever for rendering said connections operative or inoperative, of a device for operating said lever and rendering said connections inoperative when said support is moved from

one adjustment to another adjustment, substantially as specified.

3. The combination with a bench, a support pivoted on said bench, a shaft carried by said support, a drive shaft, connections from said drive shaft for rotating said first shaft, and means for raising and lowering said support, of means for moving said lever and rendering said connections inoperative incidentally to the lowering of said support, substantially as specified. 70

4. The combination with a support, a shaft carried by said support, and connections for rotating said shaft, of means for holding said support in different adjustments, and means for rendering connections inoperative incidentally to the movement of said support to one of said adjustments, substantially as specified. 80

5. The combination with a support, means for holding said support in different positions, a shaft carried by said support, and connections for operating said shaft, of a lever for rendering said connections operative or inoperative, and means for moving said lever to render said connections inoperative incidentally to the adjustment of said support in one of said positions, substantially as specified. 85

6. The combination with a support, pivots holding said support, means coöperating with said pivots for supporting said support in different positions, a shaft carried by said support, a drive wheel on said shaft, a clutch device for locking said wheel on said shaft, and means for operating said clutch device to release said wheel incidentally to the movement of said support, substantially as specified. 95

7. The combination with a support, and means for holding said support in different positions, of a shaft carried by said support, a wheel loosely mounted on said shaft, means for rotating said wheel, a clutch device for locking said wheel on said shaft, a lever for operating said clutch device, and an element to release said clutch device incidentally to the movement of said support, substantially as specified. 105

8. The combination with a frame, a support mounted on said frame, and means for holding said support in different positions, of a shaft carried by said support, a wheel loosely mounted on said shaft, a clutch device for locking said wheel on said shaft, means for rotating said wheel and thereby said shaft, a lever for operating said clutch device, and an element carried by said frame to cause said lever to release said clutch device incidentally to the movement of said support, substantially as specified. 115

9. The combination with a frame, a support pivoted upon said frame, means for holding said support in different positions 120

to which said support may be moved, a shaft carried by said support, and connections for rotating said shaft, of means for rendering said connections inoperative incidentally to the movement of said support to one of said positions, substantially as specified.

10. The combination with a movable support, a shaft carried by said support, and 10 connections for rotating said shaft, of means for holding said support in different adjustments, and a lever actuated incidentally to the movement of said support to one of said adjustments effectively to render 15 said connections inoperative, substantially as specified.

11. The combination with a movable support, two shafts carried by said movable support, gearing on said two shafts permanently in mesh, and connections for rotating one of said shafts, of means for holding said support in different adjustments, and means for rendering said connections inoperative incidentally to the movement of said support to one of said adjustments, substantially as specified.

12. The combination with a support, pivots holding one side of said support, an ele-

ment supporting the other side of said support and adjustable to hold said support in different positions, a shaft carried by said support, connections for rotating said shaft when said support is in a selected adjustment, and means for rendering said connections inoperative incidentally to the adjustment of said support in another position, substantially as specified.

13. The combination with a support, a shaft carried by said support, and a drive shaft, for operating said first-named shaft, 40 of means for holding said support in different adjustments, connections for rotating said drive shaft when said support is in one adjustment, a lever for rendering said connections inoperative, and means for operating said lever incidentally to the movement of said support to another adjustment, substantially as specified.

In witness whereof, I have signed this specification in the presence of two sub- 45 scribing witnesses.

CHARLES J. MARTH.
